UNITED STATES PATENT OFFICE.

REED ADAMS, OF LAPEER, MICHIGAN.

PRINTING-PRESS.

1,328,253.

Specification of Letters Patent.

Patented Jan. 20, 1920.

Application filed April 7, 1916. Serial No. 89,519.

To all whom it may concern:

Be it known that I, REED ADAMS, a citizen of the United States, residing at Lapeer, county of Lapeer, State of Michigan, have 5 invented a certain new and useful Improvement in Printing-Presses, and declare the following to be a full, clear, and exact description of the same, such as will enable others skilled in the art to which it pertains to make and use the same, reference being had to the accompanying drawings, which form a part of this specification.

This invention relates to printing presses, and has for its object a special control for 15 regulating the operation of small presses. This control comprises a treadle-operated clutch and brake, and the use of a supplemental treadle at the side of the machine so that an operator who is changing the 20 type form at the side is not required to have an assistant when automatic feeders are employed.

In the drawings,—

Figure 1 is a side elevation of a Gordon 25 press showing my attachments in place.

Fig. 2 is a front elevation of the skeleton of the press showing the gears, shafts and the control.

Fig. 3 is a horizontal section through a 30 part of the bottom of the press frame showing the arrangement of the treads.

It is the object of this invention to stop and start the press very quickly and to eliminate the movement of the press parts by 35 momentum after the power has been disconnected. This press is designed for work which requires frequent change of some of the printing matter, as changing the addresses in a stock letter, and consequently it 40 is desirable to stop and start the press as quickly as possible so as to lose no time.

To this end I employ a driving shaft α provided with the balance wheel b and having the male clutch part c splined thereon. 45 d is the female part of the clutch secured to the hub e of the driving pinion f that meshes with the driven gear g which operates the movable parts of the machine. This driven gear is fast to a shaft h which 50 has on its opposite end a braking drum i . A treadle j is pivoted to the base of the machine and provided with a pedal k in front of the machine. The bent link l connects with the pivoted bell crank lever m which

has a pair of forks n on its end engaging 55 the pins o on opposite sides of the end of the shifting sleeve p . This shifting sleeve has at the opposite end a shifting fork q which engages in the annular race r of the male clutch part. Ordinarily the strong spring 60 s holds the treadle up and the clutch parts disengaged. However, when the treadle is depressed through the connections already traced, the male clutch part is shifted into engagement with the female clutch part and 65 power transmitted from the drive shaft α to the driving pinion and to the moving parts of the machine.

The brake drum i is encompassed by a braking strap t fastened to one end of the 70 lever u which is pivoted to the front of the frame. Consequently when the right hand end of this lever is up, the left hand end is down, and the braking strap is pulled down over the drum i . When the pedal is 75 up and the clutch parts disengaged, this strap is kept pulled down over the drum by reason of the spring s which pulls the pedal up for the right hand end of the lever u is connected with the treadle by a connecting 80 rod v .

It is evident that the press only operates when the pedal is depressed, which serves to release the brake strap t and engage the clutch parts, thereby throwing on the power. 85 Immediately when the treadle is released, the spring s pulls it back to place, applies the brake strap t and disengages the clutch parts, thereby disengaging the power and avoiding continuance of the movement of 90 the press parts by momentum.

At the bottom of the press on the legs I journal a cross shaft w , which at the left hand end of the press is provided with a treadle x . This cross shaft w , is provided 95 with a pair of strikers y adapted to engage two arms of the treadle so that when the side treadle x is operated, the main treadle k is operated to effect the engagement or disengagement of the power and the braking operations. This auxiliary pedal allows the operation of the press by one operator who stands at the side to change the printing matter, such as addresses, and the feeding may be done by an automatic feeder 100 (not shown).

The shaft h and attached parts are mechanically closely adjacent to the form

carrying parts of the press and have but little inertia so that the stopping and starting of these parts is easily quickly effected.

What I claim is:

- 5 1. The combination with a printing press having form-bearing parts, a mechanism of small inertia adapted to actuate one of said parts and located mechanically adjacent thereto, a brake adapted to act on said actuating mechanism, a driving mechanism for said press, and means for disconnecting said driving mechanism from said form-actuating mechanism and applying the brake to the latter and for connecting said driving mechanism therewith and releasing said brake.
- 10 2. The combination with a press, of driving connections therefor provided with a disconnectible connection, a brake for the moving parts of the press, a treadle provided with suitable connections for establishing the disconnectible connection and
- 15 20

simultaneously applying the brake, the said treadle being located in front of the machine, and an auxiliary side treadle adapted to operate the same connections for the simultaneous actions already alluded to.

3. The combination with a press, of driving connections therefor provided with a disconnectible connection, a brake for the moving parts of the press, a treadle provided with suitable connections for establishing the disconnectible connections and simultaneously applying the brake, said treadle being located in front of the machine, and an auxiliary treadle provided with strikers by which the connections to the front treadle may be operated but which side treadle is not moved when the front treadle is actuated.

In testimony whereof, I sign this specification.

REED ADAMS.
